(57) **CLAIM**

The ornamental design for a portable cooler/ storage container, as shown and described.

DESCRIPTION

FIG. 1 is a front perspective view of a portable cooler/ storage container with a top cover in a closed configuration in accordance with the present design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front perspective view of the portable cooler/ storage container of FIG. 1 with the top cover in an open configuration thereof;

FIG. 9 is a front elevational view thereof;

FIG. 10 is a bottom perspective view thereof;

FIG. 11 is a top perspective exploded view thereof; and,

FIG. 12 is a bottom perspective exploded view thereof.

The broken lines shown are included for the purpose of illustrating a portion of the portable cooler/ storage container that forms no part of the claimed design.

1 Claim, 11 Drawing Sheets
